(Cl. D55—1)

To all whom it may concern:

Be it known that we, Willy E. Zimmermann and Herman E. Weidanz, both citizens of the United States, residing at Chicago, county of Cook, and State of Illinois, have invented a new, original, and ornamental Design for a Container Capping Apparatus, of which the following is a specification, reference being had to the accompanying drawings, forming part thereof.

In the drawing,

Figure 1 is a front perspective view showing the container capping apparatus of our new design;

Figure 2 is a rear perspective view of the container capping apparatus shown in Figure 1, and

Figure 3 is a top plan view of the container capping apparatus.

We claim:

The ornamental design for a container capping apparatus, substantially as shown.

WILLY E. ZIMMERMANN.
HERMAN E. WEIDANZ.
